No. 638,703.

Patented Dec. 12, 1899.

W. J. COCHRAN.
ELECTRIC ARC LAMP.

(Application filed Jan. 23, 1899.)

(No Model.)

UNITED STATES PATENT OFFICE.

WALTER J. COCHRAN, OF LE ROY, NEW YORK, ASSIGNOR, BY DIRECT AND MESNE ASSIGNMENTS, TO DAVID J. BISSELL, OF SAME PLACE.

ELECTRIC-ARC LAMP.

SPECIFICATION forming part of Letters Patent No. 638,703, dated December 12, 1899.

Application filed January 23, 1899. Serial No. 703,191. (No model.)

To all whom it may concern:

Be it known that I, WALTER J. COCHRAN, a citizen of the United States, residing in the village of Le Roy, county of Genesee, and 5 State of New York, have invented a new and useful Electric-Arc Lamp, which may be used with any kind of current, of which the following is a specification.

My invention relates to improvements in 10 electric-arc lamps, and more particularly to improvements in an arc-lamp designed to prevent the casting of a shadow.

The objects of my invention are to provide for such a lamp means of a simple and effective construction to automatically produce and maintain an arc of the desired length and in the desired position with the least possible friction of the operating parts, with the use of a small number of parts to be controlled 15 by the current and by the employment of a current of less strength than is usually necessary for a lamp of this character, to provide for maintaining the arc at all times in a fixed position when the lamp is burning, to make 20 a lamp compact in all its parts, and to secure a greater convenience in the operation of 25 cleaning and trimming.

In the accompanying drawings, Figure 1 is 30 a vertical section, partly in elevation, of a lamp with my improvements attached thereto; Fig. 2, a rear view in elevation of part of lamp, showing coil-supporting brackets; Fig. 3, a detail top plan of one of the clutches; Fig. 4, a detail plan of cover-plate, and Fig. 35 5 a section of one of arms supporting the cover on line $x-x$ of Fig. 4.

My invention is herein illustrated and described as applied to and adapted for use with an alternating inclosed arc-lamp.

40 Referring to the drawings, a is the handle of the lamp, by means of which it is supported. The handle is swiveled at its lower ends to stud-bolts b , which pass through a plate c and are rounded at their lower ends to receive 45 nuts d . Rubber washers e are clamped between a shoulder of the bolt and the plate and between the nut d and the plate, respectively, by metal washers f , and the handle thus effectively insulated from the plate and 50 its connected parts.

Secured to or preferably integral with the

plate c are the radial arms g and h , adapted to support the cover i . Arms g are provided at their outer ends with spring-catches consisting of stiff outwardly-bent vertical 55 springs j , each having a tooth or ledge k , on which a flange or bead of the cover at the upper end thereof is adapted to be supported. When the parts are in position, the ledge k engages with the flange 19 on the cover. On 60 the ends of arms h and under side thereof are cut-away portions l , which fit over the rim of the cover and by their shoulders hold the same steady. The cover i is made of lead, so as to deaden the vibrations thereof, and 65 thus prevent the vibration of the lamp itself. Integral with the plate c are the lugs m at front and rear of the lamp having arms n . Between the rear arm and corresponding standard o of a bracket p is clamped by screw 70 connections the iron core q of a choke-coil r . The core is also screwed to the arm of the front lug. The core is a horseshoe-core and is separated at the point of support between the bracket and the rear plate-lug. The bracket 75 p is provided with legs s , to which is secured by countersunk screws a circular plate or disk t , made of porcelain or other suitable insulating material. Formed on the bracket are the split sleeves v , having clamping-screws, 80 by which the screws are clamped to and support the metal tubes w , which are insulated from said sleeves by mica or other suitable insulating material. The tubes w extend from under the plates c and their lower ends 85 converge. These tubes are adapted to contain the carbons and their holders. The carbons x are placed in the tubes and are adapted to be fed down therein by gravity. Over the upper end of each carbon is fitted a metal 90 slotted sleeve y , between which and a metal plug z , driven in the sleeve, are clamped spring-brushes 1 , which are bent or curved near their upper ends, and thereby make electrical contact with the tubes. The tubes extend only a short distance below the bracket 95 p , and from the tubes the carbons extend to and through the plate t , converging a short distance below the plate and forming the arc. The carbons may converge at any suitable 100 angle, that shown in the drawings being about sixty-five degrees.

The under surface of plate *t* is made concave at the center in order to form a reflecting-surface 2 for the arc, the plate being made of or faced with suitable material for this purpose. The concavity 2 forms a corresponding convexity in the upper surface of the plate.

A small glass globe 3, hinged to the bottom of plate *t* and provided with a headed screw 10 to fasten it to the plate, is adapted to inclose the arc. A larger hinged globe 4, provided with a spring-catch and secured to the plate, incloses the smaller globe. In practice the inner globe may be dispensed with, as it will be found that the outer globe can make the arc-space sufficiently air-tight.

Mounted on bracket *p* is a working magnet 5. Within the magnet is a sliding armature or core 6. A piston-rod 7 is secured to said armature and at its upper end is provided with a piston-head 8, adapted to work in a dash-pot 9. The dash-pot is pivoted to a small yoke 10, which in turn is pivoted by right-angle arms to another yoke 11, that is riveted or screwed to the plate *c*. To the lower end of the piston-rod is secured a horizontal arm 12, of fiber or other suitable insulating material, and to each end of this arm is pivoted a link 13. The lower end of each link is pivotally connected to the jaw 14, embracing the carbon, and this jaw is also pivoted to a jaw 15, said jaws together forming a clutch adapted to engage the carbon. When the clutches are at rest and the carbon-points 35 down together and out of operation, the jaws 14 will rest evenly on the ledge 16 of the convex portion of the plate *t*.

The circuit is made through binding-post 17, working magnet 5, through one of the 40 wirings of choke-coil *r*, then through the carbons and tubes to binding-post 18.

The connection is made to any one of the several coils of the choke-coil in accordance with the pressure required to accord with the 45 voltage of the current in producing an arc of the desired length.

The operation of the invention is as follows: The carbons and other parts of the lamp are shown in working position. The 50 clutches being drawn up by the armature, the inner jaws of clutches will engage and support the carbons. The normal length of the arc is determined by the strength of the current and the strength of the current is determined by the resistance of the choke-coil. The relative location of the working magnet, armature, and clutches is such that when the 55 current is of normal strength the carbons will be held in the proper position to maintain the normal length of the arc. When the ends of the carbons in burning are consumed and separated, the resistance of the lengthened arc will break or diminish the current, lessening the attraction between the working magnet 60 and the armature and causing the latter, with the arm 12, to descend and the clutches to strike the plate *t*, whereupon the grip of the

inner jaws 14 of the clutches upon the carbons will be relaxed and the carbons will feed down and approach each other. Instantly 70 the full strength of the current will be established and the armature will be attracted upwardly to its normal position, picking up the carbons by means of the pivoted clutches, and thus striking the proper arc. The piston 75 attached to the armature and moving in the dash-pot 8 will check the movement of the armature and prevent it from being retracted too far by the renewed attraction of the magnet. It will be seen that the pick-up device 80 set forth will lift the carbons in the direction of their axes. This mode of separating the carbons to strike the arc will afford the least possible resistance to the working of the current. Since the clutches are attached directly to the carbons, which, together with the armature, slide freely in their bearings, there will be very little weight and practically no friction to oppose the movement of the adjusted parts, and hence but a slight current 85 is required for such movement. The action of the clutches is almost instantaneous, and all sputtering is thus obviated.

When the lamp is not in use and the circuit not made, the ends of the carbons will rest 95 against each other, and the jaws 14 of the clutches will rest on the ledge 16.

The ashes from the carbons will fall into the globe 3 and can be readily removed therefrom when the globe is unhooked. The 100 burned carbons can be readily removed and replaced by new ones, no set-screws or clamps being required for their support and adjustment, the slotted holder *y* having the action of a spring-holder for centering the carbon 105 and electrically connecting carbon and tube.

The insulating carbon-guiding plate *t* enables the insulation usually employed between the parts in electrical circuit and the supporting-frame to be dispensed with, while 110 the construction and location of the plate enable the reflecting-surface to be readily formed thereon.

By making the cover of lead the vibrations of the cover and lamp are neutralized. 115

The cover may be easily removed from the spring-catches and may be supported when removed by chains or other suitable means.

It is obvious that numerous changes in the details of construction may be made without departing from the principle of my invention.

What I claim is—

1. In an arc-lamp, diagonally-converging tubes fixed to the frame of the lamp, gravity-fed carbons sliding in said tubes, in combination with an arc-maintaining and pick-up device comprising an armature, pivoted clutches directly engaging said carbons, and gripping the carbons on the attracted movement of the armature, and laterally-yielding connections between said armature and clutches, whereby the carbons are picked up in the direction of their axes and at the same time separated, substantially as described. 125 130

2. In an arc-lamp, diagonally-converging carbons, a magnet and armature or core sliding in said magnet, and limited in its attracted movement solely by the resistance of the arc and strength of the current, in combination with pick-up clutches, said clutches provided with means to grip and lift said carbons, and laterally-yielding connections between said armature and clutches, whereby the carbons will be lifted in the directions of their axes and at the same time separated, substantially as described.

3. In an arc-lamp, diagonally-converging carbons, fixed holding-tubes for said carbons, a pair of pivotally-connected jaws embracing each of said carbons, a link pivoted to one of said jaws of each pair, a bar to which the opposite ends of said links are pivoted in combination with electrical means for automatically controlling the opening and closing of said jaws, and means with which said jaws are adapted to contact to relax the same, substantially as described.

4. In an arc-lamp, in combination with gravity-fed diagonally-converging carbons, fixed holding-tubes for said carbons, a vertically-moving armature and means to attract the

same, a piston attached to said armature, a dash-pot in which said piston moves, clutches consisting of pivoted jaws, means to pivotally connect said armature and a jaw of each clutch, said clutches adapted to grip the carbons for holding them in arcing position and to release them to permit their feed, said carbons adjustable in the directions of their axes and means to govern the release of the clutches, substantially as described.

5. The combination with the converging carbons of a clutching device consisting of a top cross-bar, between the carbons and above the convergence of the same, a link hung to each end of said bar, an inner clutch-jaw pivoted to each of said links, an outer clutch-jaw pivoted to the inner one, said inner and outer jaws embracing a carbon, an armature to which said top cross-bar is secured, said inner jaw adapted to grip the carbon in the upward movement of the bar, substantially as described.
